UNITED STATES PATENT OFFICE

2,243,953

AUTOMATIC GAS HEATER

William A. Graham, Houston, Tex.

Application April 13, 1939, Serial No. 267,559

8 Claims. (Cl. 53—5)

My invention relates to heaters which are adapted to employ gas as a fuel and which may be employed in connection with gas burners for toasting, heating and other similar purposes.

It is an object of my invention to provide a gas burner in which the gas which is fed to the burner also serves to operate a timing mechanism for the control of the burner.

Another object of the invention is to provide a timing mechanism for gas burners which may be automatically controlled through the flow of the gas therein.

It is a further object of the invention to provide a controlling means for the delivery of gas to the burner which will be automatically adjustable in response to the temperature of the air adjacent the burner.

It is a further object of the invention to provide a pilot light to be used in connection with the burner which is controlled through the automatically operating mechanism and responsive to the flow of gas through the device.

This invention is an improvement upon my device disclosed in my prior patent, No. 2,105,858, issued January 18, 1938, and the invention resides particularly in the construction and assembly of the parts making up my improved apparatus and reference is made to the drawings herewith for a clear disclosure of the idea.

In the drawings herewith,

Fig. 1 is a side view partly in section showing the manner in which the device is housed for operation.

Fig. 2 is a central longitudinal section through the device illustrating the operating mechanism for control of the toast-carrying rack.

Fig. 3 is a similar longitudinal section taken from the opposite side of the device.

Fig. 4 is a transverse section on the plane 4—4 of Fig. 3.

Fig. 5 is a top plan view of the device with the housing removed.

Fig. 6 is a bottom plan view of the structure shown in Fig. 5.

Fig. 7 is a side view similar to Fig. 2 but with the operating gear and the supporting plate therefor removed.

Fig. 8 is a broken detail illustrating the valve for the pilot light.

Fig. 9 is a top plan view of the gas motor employed with the invention.

Fig. 10 is a broken detail illustrating the control valve employed with the motor.

Fig. 11 is a transverse section through the motor.

Fig. 12 is a similar section taken at right angles to the one shown in Fig. 11.

Fig. 13 is a broken sectional detail illustrating the mounting of the cam disc.

5 While my invention is adapted for general use in connection with heaters I have illustrated the same as being employed upon a bread toasting device. This device includes an outer housing 1 of sheet metal which is of generally rectangular shape. The housing includes a base support 2 upon which the operating mechanism is supported. There is an upper cover plate 3 which is slotted longitudinally to allow the insertion of the toast into the same and to get a view of the operating mechanism.

With reference particularly to Figs. 3 and 4, it will be seen that the lower supporting plate 2, which forms the floor of the heating chamber, has thereon two toasting chambers each having side plates 4, which are secured to the base plate 2 at their lower sides and are extended upwardly and bent inwardly at 5 to partially enclose a heating chamber 6. Each of the side plates is equipped with a plate 7 of heat insulating material and I may have a second plate 8 between the side wall 4 and the housing 1 to further prevent the loss of heat outwardly from the chamber 6.

Centrally of each of the heating chambers 6 is a pair of guide frames 9 spaced apart to form between them a foraminated compartment 10 in which the toast is to be placed. Said compartment 10 has therefore two spaced walls made up of rods or wires spaced apart so that the heat from the chamber 6 may find ready access to the sides of the bread to be toasted. Each of the vertically extending rods 9 which make up the side walls of the compartment 10 is curved laterally at its upper end and hooked into a cross bar 11 which thus supports the rods at the upper end.

The heat is supplied to the chamber 6 through burners 12. Said burners are made up of longitudinally extending pipes preferably rectangular in cross section, as shown in Fig. 4, and with openings 13 spaced along the upper side to deliver the gas upwardly into the heating chamber.

With reference to Fig. 6, it will be seen that there are pipes 12 on opposite sides of each of the chambers 6. These two pipes are connected by a cross pipe 14, which in turn has a forwardly extending member 15 connected with the gas pipe 16. The bottom wall 2 of the heating chamber is perforated, as shown at 17, to allow the pas-

sage of air to the burner through the lower portion of the chamber.

As will be seen from Fig. 6, the gas conducting pipes 16 have connection through the pipe 18 with both of the burners. Said pipe 16 extends upwardly through the floor plate 2 to receive gas from the pipe 19, which extends into the motor 9, as will be now described.

Referring to Figs. 9 to 16, inclusive, I have disclosed a motor which is in all respects practically the same as the motor disclosed in my prior Patent No. 2,105,858 above referred to. It is adapted to receive thereto, through an inlet pipe 20, a supply of gas coming from any source of gas under pressure, such as the usual household gas connections.

Said pipe 20 delivers the gas into an upper chamber 21 formed in a housing 22 which is supported upon the upper end of the motor 23. The gas from the chamber 21 may pass downwardly to the two opposed gas chambers in the motor.

The motor includes an upper plate 24 with a central downwardly extending outlet passage 25 for the gas which gas is delivered through the pipe 19 to the burner. The upper end of the passage 25 is covered by a valve plate 26. Said valve plate fits closely against an upper seat member 27 fitted into the plate 24. Through the plate 27 are a series of openings 28, four in number, as will be seen from Fig. 10. The valve plate has a downwardly extending rim 29 fitting closely against the valve seat.

The plate 26 has a central opening at its upper side to receive a pin 30 formed eccentrically on the lower side of a rotating shaft 31 and it will be seen that when the shaft 31 is rotated the disc will be moved in a path about the shaft so that one after another of the openings 28 will be exposed to receive the gas from the chamber 21. While one of said openings is thus exposed to receive the gas the opposite opening 32 will be connected with the exhaust opening 25 previously referred to. Connected with each of the openings 32 and 32' is a passage leading to one of the chambers of the motor. There are two chambers which are practically identical in construction, there being a flexible diaphragm 33 dividing each chamber into compartments 34 and 35. Centrally of the diaphragms is a post which has a pair of forked arms 36 on one side thereof, said arms being connected with a lever 37, the opposite end of which is fixed to a shaft 38 journaled at each of its ends in the walls of the housing. The upper end of the shaft 38 projects through a stuffing box 39, into the upper housing 22 and has a laterally extending arm 40 thereon which acts as a crank arm, the free end of which is connected by means of a link 41 to a crank pin 42 upon the upper side of a disc 43 secured on the shaft 31 previously referred to.

It will be seen that the two chambers on opposite sides of the motor housing are identical in construction and that as gas is fed in proper sequence into these chambers the diaphragm 33 will be moved first in one direction and then in the opposite direction, and the movement of these diaphragms being properly timed, one will be moving outwardly while the other is moving inwardly and vice versa. The upper ends of the shafts 38 are bent in directions approximately at right angles to each other, as will be seen from Fig. 9. Thus the movement of the diaphragms will move the arms 40 so as to give a rotating movement to the disc 43 and the shaft 31 in a counterclockwise direction, as shown in Fig. 9,

With the rotation of the shaft 31, the valve plate 26 will be moved so as to allow the passage of gas into the diaphragm chambers in the proper sequence to obtain the movement of the diaphragms and the shaft, as has been described.

The rotation of the shaft 31 will cause the movement of the pin 42 in a circle concentric with the shaft 31. Said pin 42 is extended upwardly to engage within a disc 44, which is fixed to the lower end of a shaft 45 supported in a bracket 46 in the housing 22. The upper end of the shaft 45 is journaled rotatably in a plug 47 screwed within the upper end of the housing. Formed upon the shaft 45 is a worm gear 48 which is operatively connected with a gear 49 upon a shaft 50, which is extended laterally through a stuffing box 51 in the housing 22 and has formed on its outer end a small gear 52.

It will be noted that the gas which is fed into the upper housing 22 through the pipe 20 may pass freely downwardly through the upper housing 22 to the motor and will be delivered by means of the operation of the valve 26 in sequence to the chambers of the motor, so as to cause the operation of the diaphragms and the rotation of the shafts which operate in turn the power shaft 31. In this way rotation may be communicated in the manner shown to the laterally extending gear 52. This motor, as will be seen, operates in the same manner as does the motor of my prior patent.

Mounted within the heating chamber 6 is a toast-carrying rack 53. With reference to Fig. 5, it will be seen that the rack 53 has arms 54 extending longitudinally of the heating chambers 6 and movable simultaneously in a vertical direction along the rods 9 previously described. Each of the arms 54 has laterally extending lugs 55 thereon which are formed with openings to receive the rods 9 so that the rack may be slidable vertically along said rods. Said frame 53 is connected at its forward end to a frame member 56 which has a forwardly projecting handle 57. There are upwardly and downwardly extending arms on the frame member 56 which are pivotally connected to an upper lever arm 58 and to a lower lever arm 59. Said arms 58 and 59 are parallel and it will be seen therefore that the toast-carrying rack, including the supporting arms 54, will remain horizontal during the movement of the levers 58 and 59.

The forward end of the lever 58 is pivoted at 60 upon a frame plate 61. As will be seen particularly from Fig. 3, the forward end of the lever 58 is extended beyond the pivot and has a quadrant-shaped end. The lower end of said quadrant-shaped head 62 has thereon a laterally extending post 63, which is adapted to engage with the latching mechanism which will be presently described.

The lower lever 59 is pivoted at 64 to the frame plate 61 and has a downwardly extending arm 65, which is connected at 66 to a link 67, which has a cross arm thereon engaging over the valve stem 68. The lower end of the arm 65 is secured at 69 to a tension spring 70, which is connected at its other end to the base plate at 71.

The gear 52 upon the motor shaft engages with a large gear 72, which is mounted upon a shaft 73 supported in plates 74 in the housing. The shaft 73 has thereon a cam disc 75. Said disc has two laterally extending arms 76 and 77 thereon, which are adapted to engage with the latching mechanism. On one side of said disc is a laterally extending cam which has an in-

clined surface 79 thereon, which engages with a similar inclined cam surface 80 formed upon a downwardly depending arm 81 pivotally connected at 82 to a valve housing 83.

The valve housing 83 encloses the pilot light operating valve shown in Fig. 8. It will be seen that the housing 83 in that figure has an inlet pipe 84 and an outlet pipe 85. The interior of the valve chamber 86 in the housing has a passage from the inlet to the outlet pipe controlled by a valve 87, said valve fitting within a seat in the passage between the two pipes and has a stem 88 extending through the forward wall of the chamber and secured at its outer end to a head 89. A spring fitting about the valve stem tends to hold the head 89 outwardly to close the valve in the passage. When the arm 81 is moved against the head 89 it will move the valve 87 to open position, allowing the passage of gas from the pipe 84 to the pipe 85.

The movement of the shaft 73 will carry the cam disc 75 around in a clockwise direction. The driving connection between the cam disc and the shaft 73 is shown in Fig. 13. The shaft 73 extends through the wall or plate 74 and has secured thereto adjacent the wall a friction disc 90, said disc being held rotatable with the shaft. The cam disc 75 is held in frictional engagement with the disc 90 by means of a spring 91 on the shaft bearing at one end against the head 92 of the shaft and at the other against the cam disc. Thus the said cam disc is held normally in frictional engagement with the friction disc 90 and will rotate therewith. The cam disc may, therefore, be rotatable independently of the shaft 73 and disc 90 by a slipping of one relative to the other.

As will be seen in Fig. 7, the cam disc 75 has a laterally extending arm 93 adjacent one edge thereof and an opposite arm 94 somewhat longer than the arm 93, which as will be later noted, is adapted to be engaged by an arm of the frame to move the cam disc.

When the frame is moved to its lowest position to bring the toast-carrying rack adjacent the burner, the laterally extending pin 63 thereon is engaged within a notch 95, formed in the upper side of the latching member 96. Said latch is pivoted at one end upon a pin 97 secured within the frame 61. Said latch is extended upwardly in an inclined direction and as a cam surface 98 adjacent the notch 95, which tends to depress the latch as the pin 63 on the frame is swung upwardly into latching position. The upper end of the latch 96 has a finger 99 thereon toward the extremity of which is a pin 100 connected to a spring 101 secured at its upper end to a pin 102, so as to exert a pull upwardly upon the latch.

There is a hand lever 103 which is extended from the upper end of the housing downwardly for connection at its lower end to an arm 104, which is in turn directed downwardly and pivoted upon the pin 97 previously described. On the arm 104 is a forwardly projecting finger 105, which has a cam surface 106 engaging against a wedge-shaped block 107. Said block rests upon the upper end of the latching lever and it will be understood that when the arm 105 is depressed it will move the wedge block 107 and the latch lever downwardly to disengage the latch from the pin 63 upon the lever 58.

The wedge block 107 is pivotally connected to a link 108, which is in turn connected to a pivot

pin 109 at the outer end of a crank arm 110. Said crank arm is fixed upon a shaft 111, which projects through the plate to the opposite side thereof.

With reference to Fig. 3, it will be seen that I have a post 112 mounted upon the base plate 2 and extending upwardly at the forward side of the housing. There is formed thereon an inwardly extending arm 113 which projects into the heating chamber at a point between the two burners. At its forward end is a block 114 upon the upper surface of which is secured a plate 115 of a thermostat. This metal is adapted to be moved upwardly at its forward end 116 when subjected to heat. This is a common type of thermostat now in general use. The upward movement of the member 115 will communicate movement to a link 117, which is secured at its upper end to a rocking arm 118 mounted upon the shaft 111. It will be seen that there are a plurality of openings in the end 116 of the thermostat arm and also in the rocking arm. I am thus enabled to give a partial rotation to the arm 111 in response to the action of the heat in the interior chamber of the toaster which is adjustable to suit the conditions of each particular installation. Referring back to Fig. 7, it will be noted that the side of the arm 103 presented inwardly is formed with a cam surface 119 shown in dotted lines in that figure. Thus when the cam disc is rotated in a clockwise direction the pin 93 will contact with the cam surface 119 and depress the arm 104 so as to move the cam block 107 downwardly to unlatch the latch member and release the toast-carrying rack. The rotation of the cam at a uniform predetermined speed due to the operation of the motor, will bring the pin 76 into contact with the cam surface 119 after a predetermined interval. This interval may be shortened, however, when the heating chamber heats up to such an extent as to effect the thermostat and thus cause a rotation of the shaft 111. Said rotation will be in a clockwise direction, as shown in Fig. 7, and will exert a pull upon the link 108 to move the wedge block 107 to the right, thus bringing the wider portion of the wedge block beneath the arm 105. In this manner the arm 105 will be moved upwardly as the wedge block moves to the right and the cam surface 119 will be more quickly engaged by the pin 76 to release the latch. By this means the latch will operate after a somewhat shorter interval where the heating chamber is heated up than it will where the heating chamber has been cooled to some extent. This will serve to discharge the toast at the proper time before it has had an opportunity to burn.

When the latch is operated to release the pin 63, the spring 70 which exerts a tension upon the lower lever 59 will act to throw the two levers 58 and 59 upwardly carrying with it the toast supporting rack 54 and thus remove the toast from the heating chamber.

The control of the gas which is fed to the motor and to the burner will now be described. With reference to Figs. 3 and 6, it will be seen that the gas coming to the device will pass through the pipe 120 into a valve chamber 121. Said valve chamber is formed with a tapered seat 122 to receive a tapered valve member 123. Said valve closes the passage of gas from the chamber 121 to the chamber 124. It has a stem 125 projecting through a stuffing box into engagement with a head 126 having thereon the

outwardly extending stem 68 previously referred to.

The chamber 121 is connected with the pipe 127 which, as seen in Fig. 5, passes into the upper chamber through the port 20 previously noted. The gas then passes through the motor and outwardly through the pipe 19 to connect with the pipe 16 leading to the burners. It is therefore to be noted that the gas which serves to operate the motor exhausts through the pipe 16 and 18 10 to feed the burners below the heating chambers.

It will be understood that the release of the toast-carrying rack will be accomplished automatically under usual operating conditions but that the release of the latch may be accomplished by the movement of the lever arm 103. The device is entirely enclosed within the outer housing 3 and to engage the lever 103 a push rod 128 is mounted longitudinally of the housing and upon the upper plate 3. Said push rod has at its inner end a contacting arm 129, which is slidable upon a plate 130 and is in position to engage with the lever arm 103 and push it to the left to release the toast-carrying rack.

A spring 13 is provided to withdraw the push rod when the arm 103 has been moved. This push rod has a handle 132 at the forward side of the housing for the operation of the rod.

The operation of the device has been already described. It will be understood that when the toast is to be toasted it is placed upon the toast-carrying arms 54 through slots in the upper end of the housing and the handle 51 is depressed to move the rack into position adjacent the burners and to carry the pin 63 on the upper lever arm into engagement with the latch 96 as was previously described. This will hold the rack in its lower position until released. The movement of the two lever arms 59 as the rack is depressed will also move the arm 65 upon the lower lever arm 59 to open the passage of gas to the motor. The motor will operate as previously described to rotate the small gear 52 and the larger gear 72 connected therewith so as to rotate the operating shaft 73. The gas will pass from the motor to the burners and the gas at the burners will be ignited from the pilot light.

The pilot light is fed with gas from the main line 120, as seen in Fig. 6. A branch pipe 133 leads off from the chamber 124 and has therein a valve member 134 which may be employed to regulate the rate of supply of gas through the pipe 133. Said pipe 133 passes upwardly through the bottom of the housing, as shown in Fig. 5, and enters the valve chamber 83 through 35 inlet 84. When the valve 87 in said valve chamber is opened it will pass outwardly through the pipe 35 and will pass back downwardly through the base plate and issue at 135, as shown in Fig. 6, and will thence be conducted to the pilot lights 136 and 137 and from thence back through the valve 138 to the valve chamber 121. The structure of the pilot light may be seen at the left of Fig. 3. It includes an upstanding arm having a nozzle 139 at the upper end positioned adjacent the burner 13.

It will be noted that when the toast rack is moved downwardly it will move the cam disc 75 into a position with the cam 78 thereon bearing against the cam surface upon the lever arm 81, thus tending to depress the head 89 upon the control valve 87 and thus permit the passage of gas to the pilot light. It will be understood that the gas valves 122 and the valve 87 in the pilot light control valve will be seated loosely so as 70 75 to allow the passage of some gas to the pilot light at all times but that when the valve 87 is depressed by the arm 81 as described a sufficient amount of gas will be fed to the pilot light to cause a strong upward flame while the cam 78 is in contact with the arm.

After the rack has been lowered and latched as described the gas valve will be opened due to the movement of the arm 65 on the rack to raise said arm in engagement with the end of the valve stem 68 to open the valve and feed the gas to the burners as described. This gas passing by way of the motor will cause the rotation of the cam 75 in a clockwise direction so as to move the pin 93 thereon into position to release the latch after a predetermined time ordinarily sufficient to toast the bread upon the rack. This period may be shortened as previously described by the thermostat acting to move the wedge block 107. When the latch 96 has been depressed sufficiently through the engagement of the pin 93 with the arm 104 the rack will be free to be thrown upwardly into its original position through the action of the spring 76.

When the arm 58 is thus moved upwardly engagement is had between an arm 140 and the pin 94 upon the cam disc. Said arm 140 is connected adjustably with the forward end of the lever 58, as will be seen in Fig. 3. The arm has a downwardly projecting portion which is slotted to receive a set screw 141, through which it may be adjusted toward and away from the pin 94. There is a branch 142 on the arm 140 which projects laterally within the path of the pin 94 upon the cam disc 75. Thus when the arm 58 is depressed the arm 142 will be moved upwardly away from the pin 94 allowing free rotation of the disc 75. When the arm 58 is released by the disengagement of the latch as described the arm 58 will be thrown upwardly at the forward end and downwardly at the end 62 so as to throw the arm 142 downwardly with some force, bringing said arm into engagement with the pin 94 and thus throwing it back into its original position shown in Fig. 3. This is accomplished by slipping the cam disc 75 on the friction disc 90 adjacent thereto. It will be understood that due to the meshing of the gears 52 and 72 the shaft 73 will not be rotatable in a counter-clockwise direction but the disc 75 may be frictionally moved relative to the shaft so as to allow the cam disc 75 to be rotated back to its original position so that the operations may be again resumed in the order described.

My present invention has certain advantages over the structure shown in my prior patent above referred to in that the control of the gas to the motor and to the burner is more positive and reliable. Furthermore, the control of the period during which the toast is subjected to the heat is more satisfactory in that it operates in response to the temperature within the heating chamber or oven. As the said temperature is raised the period that the toast is exposed within the oven is decreased so that in all cases the toast will be discharged at the proper time without burning. The further advantages of this construction will be apparent to those skilled in the art.

What is claimed is:

1. A gas burner, a food carrying rack, means to move said rack toward said burner, means to automatically latch said rack in position adjacent said burner, a spring tending to move

said frame away from said burner, a gas conducting line leading to said burner, a normally closed valve in said line, means operated by said rack moving means to open said valve, a motor operated at a uniform speed by the flow of gas to said burner, means operated by said motor to release said rack after a predetermined interval, and means responsive to the heat adjacent said burner to adjust said last means to shorten said interval as said burner heats up.

2. A gas burner, a food carrying rack, means to move said rack toward said burner, means to automatically latch said rack in position adjacent said burner, a spring tending to move said frame away from said burner, a gas conducting line leading to said burner, a normally closed valve in said line, means operated by said rack moving means to open said valve, a motor operated at a uniform speed by the flow of gas to said burner, means operated by said motor to release said rack after a predetermined interval, a thermostat adjacent said burner, a shaft operatively connected for rotation by said thermostat in response to heat adjacent said burner, and means operated from said shaft to adjust said last means to shorten said time interval.

3. A gas burner, a food carrying rack, means to move said rack toward said burner, means to automatically latch said rack in position adjacent said burner, a spring tending to move said frame away from said burner, a gas conducting line leading to said burner, a normally closed valve in said line, means operated by said rack moving means to open said valve and deliver a uniform flow of gas through said line, a motor connected in said line and operated at a constant speed by said gas, a gear operated from said motor, a cam disc operated from said gear, a lever pivoted adjacent said latch and movable to release said latch, means on said cam disc to move said lever after a predetermined period of operation, a wedge block between said last named means and said lever and means responsive to the rise of temperature at said burner to move said wedge block to shorten the interval before the release of said latch.

4. In a device of the character described, a gas burner, a gas line leading to said burner, a normally closed valve in said line, a gas operated motor in said line between said valve and said burner, a food carrying rack, a lever supporting said rack and pivoted to swing said rack to and from said burner, a latch positioned to automatically engage and latch said lever in position with said rack adjacent said burner, means on said lever to open said valve, a shaft rotatable at a uniform speed by said motor, a cam disc thereon, a releasing lever pivoted adjacent said latch, an arm on said lever, a wedge block between said arm and said latch, a pin on said cam disc positioned to engage said lever after a predetermined period of rotation, a thermostat adjacent said burner, and means operable by said thermostat to move said wedge block to shorten the interval before said latch is released.

5. In a device of the character described, a gas

burner, a gas line leading to said burner, a normally closed valve in said line, a gas operated motor in said line between said valve and said burner, a food carrying rack, a lever supporting said rack and pivoted to swing said rack to and from said burner, a latch positioned to automatically engage and latch said lever in position with said rack adjacent said burner, means on said lever to open said valve, a shaft rotatable at a uniform speed by said motor, a cam disc thereon, a releasing lever pivoted adjacent said latch, an arm on said lever, a wedge block between said arm and said latch, a pin on said cam disc positioned to engage said lever after a predetermined period of rotation, a thermostat adjacent said burner, a shaft rotatable by said thermostat in response to the heating up of said burner, a crank arm thereon, and a link on said crank arm connected with said wedge block to move said block and shorten the interval before which said latch is released.

6. A gas burner, a food carrying rack, means to move said rack toward said burner, means to automatically latch said rack in position adjacent said burner, a spring tending to move said frame away from said burner, a gas conducting line leading to said burner, a normally closed valve in said line, means operated by said rack moving means to open said valve, a gas operated motor between said valve and said burner, a pilot light adjacent said burner, a pipe connected with said gas line and connected with said pilot light, a control valve in said pipe, a cam disc operated by said motor, means on said disc to cause the release of said latch after a predetermined period, and additional means on said disc to open said control valve and increase the passage of gas to said pilot light.

7. A heating chamber, a main gas burner therein, a pair of parallel levers pivoted adjacent said chamber, a food carrying rack mounted on said levers and movable toward said burner, a spring tending to move said rack to position away from said burner, a gas line leading to said burner, a motor in said line, a latch for said levers to retain said frame in lowered position, a pilot light burner adjacent said main gas burner, a branch line leading thereto, a pilot light valve in said branch line, a cam disc rotatable from said motor at a uniform speed, means responsive to the rotation of said disc to release said latch after a predetermined interval, a lever arm movable by said disc to open said pilot light valve, and means on said disc operable when said rack is moved to a position adjacent said burner to rotate said disc to cause said disc to move said lever arm.

8. In a gas fired toaster, a food rack, a latch to hold said rack in position to toast the food therein, adjustable means operated by the gas fuel to release said latch, and additional means responsive to the heat adjacent the rack to adjust said first means to vary the interval before release in proportion to such heat.

WILLIAM A. GRAHAM.
